UNITED STATES PATENT OFFICE

ALLAN C. KENNEDY, OF KELSO, WASHINGTON

SAWDUST BURNER

Application filed March 25, 1929. Serial No. 349,760.

The present invention relates to improvements in domestic burners for house heating wherein the waste from sawmills such as sawdust, wood waste and the like is utilized as the fuel.

One of the important objects of the invention is to provide a sawdust burner attachment for heating stoves wherein the same includes an improved grate construction, the latter being provided with draft openings to aid in the combustion of the fuel.

Another important object resides in the provision of an angular chute for disposition within the burner and for further cooperation with the outer edge of the grate for facilitating the feeding of the sawdust to the fire-box portion of the burner, the lower portion of the vertically disposed angular chute being also formed with draft openings to aid in the combustion of the fuel.

Another object is to provide a sawdust burner attachment for stoves wherein the parts are so arranged as to permit the same to be readily and easily assembled or disassembled and to further permit the adjustment of the grate as well as the angular chute.

A still further object is to provide a sawdust burner attachment of the above-mentioned character which is simple in construction, inexpensive, strong and durable and further well adapted for the purposes for which it is designed.

Other objects and advantages of the invention will become apparent from the following description when taken in connection with the accompanying drawings.

In the accompanying drawings wherein like reference characters indicate corresponding parts throughout the same:

Figure 1 is a front elevation of the sawdust burner embodying my invention showing the manner in which the same is attached to a convenient heating stove.

Figure 2 is a side elevation, the burner being shown in section.

Figure 3 is a horizontal section taken ap-

proximately on the line 3-3 of Figure 2 looking downwardly.

Figure 4 is a detail perspective view of the angular chute.

Figure 5 is a similar view of the grate; 55 and

Figure 6 is a detail perspective view of one of the notched blocks for supporting the grate in any vertically adjusted position. 60

In the drawings wherein for the purpose of illustration is shown the preferred embodiment of my invention, the numeral 1 designates generally a heating stove of any conventional construction, the opening that leads to the ash pit being designated at 2. 65 My improved saw dust burner comprises a substantially L-shaped casing denoted generally by the reference character 3, the same being substantially rectangular in cross section. The base portion of the L-shaped casing has its free end extending into the opening 2 of the stove 1 and a flange 4 extends around the side of the outer end portion of the base of the L-shaped casing for engagement with the outer face of the front side of the stove adjacent the opening 2 to limit the inward sliding movement of the casing with respect to the ash pit of the stove. 70 To further support the casing in a rigid manner, there is provided the brace 5 that is secured at one end of the inner side of the upstanding portion 6 of the L-shaped casing and the other end of this brace is secured to the front of the stove in the manner as more clearly disclosed in Figure 2 of the drawings. 75 80 85

A funnel-shaped hopper 7 is formed at its lower discharge end with the reduced neck portion 8 that is removably fitted in 90 the upper end of the leg or upstanding portion 6 of the L-shaped casing 3, and a removable lid 9 is provided for the open top of the hopper 7. The casing 3 is preferably constructed of cast iron while the hopper 95 may be constructed of sheet metal although it is to be understood that I do not wish to limit myself to the particular material from which the casing and the hopper are formed. 100

5 The outer side of the leg portion 6 of the L-shaped casing 3 is formed adjacent its lower end with the draft opening 10 and a movable closure 11 is associated with this draft opening. Below the draft opening, there is arranged in the outer side of the leg portion 6 a clean-out opening that is normally closed by means of the hinged door shown at 12.

10 The base portion of the L-shaped casing 3 constitutes what I term the fire box or combustion chamber 13 and removably arranged within the bottom of the fire box or combustion chamber is the cast iron grate shown at 14 in Figure 5. The inner end of this grate is formed with a downwardly extending lip 15 while a transverse rib 16 is formed on the underside of the outer end portion of the grate 14 for a purpose to be presently described. The outer end portion of the grate 14 is formed with a series of air holes 17 as also clearly shown in Figure 5.

15 Wedge-shaped blocks such as are shown at 18 in Figure 6 are adapted to have their flat bottom faces resting on the bottom of the casing 3 and the inclined upper edges of these blocks are formed with spaced notches 19 for receiving the rib 16. This construction provides a means whereby the outer 20 end portion of the grate 14 may be vertically adjusted with respect to the bottom of the fire box 13 and this grate 14 is of such a length as to terminate a suitable distance inwardly of the outer side of the leg portion 30 6 of the casing as suggested very clearly in Figure 2.

25 A stop 20 extends upwardly from the bottom of the inner end portion of the fire-box for engagement with the depending lip 15 to limit the inward sliding movement of the grate 14 in the manner as also clearly shown in Figure 2.

30 Adapted for cooperation with the grate 14 is the angular chute denoted generally by 45 the numeral 21 and which chute is clearly illustrated in Figure 4 of the drawings. This chute is arranged in a vertical manner in the lower outer portion of the angular casing 3, the upper edge of the upper section 50 22 being beveled as indicated at 23 to fit snugly against the inner face of the front wall of the leg portion 6 while the lower section 24 of the angular chute 21 is formed at its free lower edge with the notched segments 25, the outer edge portion of the grate 14 being adapted to engage in any one of the notches 26 formed in the segments in the manner as clearly shown in Figure 2.

55 The lower section 24 of the angular chute 21 is further provided adjacent its lower edge with spaced air openings 27.

60 The lower edge of the angular chute 21 is spaced approximately one-quarter of an inch from the outer edge of the grate 14. 65 The notched segments 25 cooperate with the

outer or adjacent edge of the grate 14 for adjusting the angular chute 21 whereby to regulate the flow of the sawdust from the hopper 7 to the fire-box or combustion chamber 13. The coarser the sawdust is, the faster it will feed or crowd down on the fire. By raising the grate and the chute 21, the feeding of the sawdust to the fire-box may be regulated.

65 To start the fire, the hopper 7 is removed from the upper open end of the leg portion of the L-shaped casing 3, and pieces of paper are pushed downwardly into the fire-box 13 and the same is ignited after which a small quantity of saw dust is sprinkled over the burning paper to start the burning of the fuel after which the hopper is placed in position and is filled up with the sawdust. The sawdust will by gravity be delivered to the fire-box 13 where the same will burn and form a honeycomb and with a very little draft, a gas like flame will enter the stove 1 for effectively heating the room in which the stove is located.

70 It will thus be seen from the foregoing description, that I have provided a sawdust burner attachment for stoves that will at all times be positive and efficient in its operation and due to its simplicity, the parts may be properly adjusted whenever necessary and 75 may furthermore be assembled or disassembled.

75 While I have shown the preferred embodiment of my invention, it is to be understood that minor changes in the size, shape and arrangement of parts may be resorted to without departing from the spirit of the invention or the scope of the appended 80 claims.

85 What is claimed is:

1. A burner of the class described comprising a casing including a fire-box, the inner end of the fire-box being open, a grate arranged in the bottom of the fire-box and provided with air holes in the outer end portion thereof, means for adjustably spacing the outer end portion of the grate with respect to the bottom of the fire-box, the outer end of the fire-box being provided with a draft opening, and means within the outer end portion of the fire-box for delivering fuel onto the grate, said means including an inclined chute, the lower edge thereof terminating adjacent the outer edge of the grate, the upper edge of the chute adapted to engage with the outer side of the casing, and means carried by the lower edge of the chute for engagement with the adjacent edge of the grate to support the latter or to support the chute in position in the casing. 105

110 2. A burner of the class described comprising a casing including a fire-box, the inner end of the fire-box being open, a grate arranged in the bottom of the fire-box and provided with air holes in the outer end 115

portion thereof, means for adjustably spacing the outer end portion of the grate with respect to the bottom of the fire-box, the outer end of the fire-box being provided 5 with a draft opening, and means within the outer end portion of the fire-box for delivering fuel onto the grate, said means including an inclined chute, the lower edge thereof terminating adjacent the outer edge of the grate, the upper edge of the chute adapted to 10 engage with the outer side of the casing, and means carried by the lower edge of the chute for engagement with the adjacent edge of the grate to support the latter or to support the chute in position in the casing, said last-mentioned means comprising a notched segment.

3. A burner of the class described comprising in combination with a heating stove, 20 of a substantially L-shaped casing open at its respective ends, the free end of the base portion of the casing adapted to extend into the ash pit of the stove, the base portion of the L-shaped casing comprising a fire-box, a fuel hopper supported in the upper end of the leg portion of the L-shaped casing, a 25 grate arranged within the bottom of the fire-box and provided with air holes in the outer end portion thereof, means for adjustably supporting the outer end portion of the 30 grate with respect to the bottom of the fire-box, the outer side of the leg portion of the L-shaped casing being provided with a draft opening adjacent the lower end thereof, and 35 means within the outer lower portion of the casing for feeding the fuel onto the apertured grate.

4. A burner of the class described comprising in combination with a heating stove, 40 of a substantially L-shaped casing open at its respective ends, the free end of the base portion of the casing adapted to extend into the ash pit of the stove, the base portion of the L-shaped casing comprising a fire-box, a fuel 45 hopper supported in the upper end of the leg portion of the L-shaped casing, a grate arranged within the bottom of the fire-box and provided with air holes in the outer end portion thereof, means for adjustably sup- 50 porting the outer end portion of the grate with respect to the bottom of the fire-box, the outer side of the leg portion of the L-shaped casing being provided with a draft opening adjacent the lower end thereof, and means 55 within the outer lower portion of the casing for feeding the fuel onto the apertured grate, said means comprising an inclined chute, the upper edge thereof engaging with the outer side of the intermediate portion of the leg of the casing, and means carried by the lower 60 edge portion of the chute for engagement with the outer edge of the grate to support the chute in position.

5. A burner of the class described comprising in combination with a heating stove,

of a substantially L-shaped casing open at its respective ends, the free end of the base portion of the casing adapted to extend into the ash pit of the stove, the base portion of the L-shaped casing comprising a fire-box, 70 a fuel hopper supported in the upper end of the leg portion of the L-shaped casing, a grate arranged within the bottom of the fire-box and provided with air holes in the outer end portion thereof, means for adjust- 75 ably supporting the outer end portion of the grate with respect to the bottom of the fire-box, the outer side of the leg portion of the L-shaped casing being provided with a draft opening adjacent the lower end thereof, and means within the outer lower portion of the casing for feeding the fuel onto the apertured grate said means comprising an inclined chute, the upper edge thereof engaging with the outer side of the intermediate portion of the leg of the casing, and means carried by the lower edge portion of the chute for engagement with the outer edge of the grate to support the chute in position, 80 said last-mentioned means comprising a 85 notched segment.

6. A burner of the class described comprising in combination with a heating stove, of a substantially L-shaped casing open at its respective ends, the free end of the base portion of the casing adapted to extend into the ash pit of the stove, the base portion of the L-shaped casing comprising a fire-box, a fuel hopper supported in the upper end of the leg portion of the L-shaped casing, a 90 grate arranged within the bottom of the fire-box and provided with air holes in the outer end portion thereof, means for adjustably supporting the outer end portion of the 95 grate with respect to the bottom of the fire-box, the outer side of the leg portion of the L-shaped casing being provided with a draft opening adjacent the lower end thereof, and means within the outer lower portion of the 100 casing for feeding the fuel onto the apertured grate of the fire-box, the outer side of the leg portion of the L-shaped casing being provided with a draft opening adjacent the lower end thereof, and means within the outer lower portion of the 105 casing for feeding the fuel onto the apertured grate of the fire-box, the outer side of the leg portion of the L-shaped casing being provided with a draft opening adjacent the lower end thereof, and means within the outer lower portion of the 110 casing for feeding the fuel onto the apertured grate of the fire-box, the outer side of the leg portion of the L-shaped casing being provided with a draft opening adjacent the lower end thereof, and means within the outer lower portion of the 115 casing for feeding the fuel onto the apertured grate of the fire-box, the outer side of the leg portion of the L-shaped casing being provided with a draft opening adjacent the lower end thereof, and means within the outer lower portion of the 120 casing for feeding the fuel onto the apertured grate of the fire-box, the outer side of the leg portion of the L-shaped casing being provided with a draft opening adjacent the lower end thereof, and means within the outer lower portion of the 125 casing for feeding the fuel onto the apertured grate, said means comprising an inclined chute, the upper edge thereof engaging with the outer side of the intermediate portion of the leg of the casing, and means carried by the lower edge portion of the chute for engagement with the outer edge of the grate to support the chute in position, the lower edge portion of the chute being formed with air holes.

In testimony whereof I affix my signature. 125
ALLAN C. KENNEDY.
